UNITED STATES PATENT OFFICE.

EMERSON T. MORRIS, OF CONSTITUTION, OHIO.

WIRE-STRETCHER.

1,142,352.

Specification of Letters Patent.

Patented June 8, 1915.

Application filed January 23, 1914. Serial No. 813,960.

To all whom it may concern:

Be it known that I, EMERSON T. MORRIS, citizen of the United States, residing at Constitution, in the county of Washington and 5 State of Ohio, have invented certain new and useful Improvements in Wire-Stretchers, of which the following is a specification.

This invention relates to improvements in devices for stretching wire, more particularly the strand wires of fences, and has for one of its objects to simplify and improve the construction and increase the efficiency and utility of devices of this character.

Another object of the invention is to provide a simply constructed device which may be applied without structural change to fence posts or other stationary supports of varying sizes, and which may be readily applied to stretching the strand wires of ordinary fences, fence webbing, chicken fencing and the like, without structural change either in the device or in the fence material.

Another object of the invention is to provide a simply constructed device which may be applied to posts or other stationary supports at any point thereon and movable longitudinally of the post to adapt it to the different strand wires or to the webbing at 30 different points.

With these and other objects in view the invention consists in certain novel features of construction as hereinafter shown and described and then specifically pointed out in 35 the claim; and in the drawings illustrative of the preferred embodiment of the invention. Figure 1 is a plan view of the improved device applied. Fig. 2 is a side elevation of the same.

40 Corresponding and like parts are referred to in the following description and indicated in all the views of the drawings by the same reference characters.

The improved device includes a stock or 45 bar 10 having a lateral offset 11 at one end, the latter being preferably oblique to the longitudinal axis of the member 10 at an acute angle thereto. At its opposite end the member 10 is provided with a laterally di- 50 rected stud 12 which is also offset to the longitudinal axis of the stock as shown.

The stud 12 is connected to the stock 10 by an L-shaped projection 13, and is designed to pivotally support an operating lever 15, the 55 center of the lever being located in alignment with the offset 11 at an intermediate

point, as illustrated in Fig. 1, the object to be hereinafter explained.

The stud 12 is preferably provided with a stop collar 16 and with a suitable holding device such as a cotter pin 17 to retain the lever 15 in position, while at the same time permitting the lever to be freely oscillated upon the stud.

The stock 10 is provided with a plurality 65 of transverse apertures 18 through one of which a pin 19 is adapted to be inserted as shown in Figs. 1 and 2, the object to be hereinafter explained.

Connected in any suitable manner to the 70 lever 15 at opposite sides of its pivotal point are rods 20-21, the rods terminating respectively in hooks 22-23. The hooked rods are mounted to swing freely upon the lever 15 as by links 24-25 and are designed to 75 engage by their hooked terminals 22-23 in the links of a pull chain 26, the links of the chain being sufficiently open to receive the hooks.

At its outer end the chain 26 is provided 80 with a suitable wire gripping device represented conventionally at 27, but as the grip device forms no part of the present invention it is not deemed necessary to further describe the same.

With a device thus constructed, the operation is as follows: A post of suitable strength, for instance one of the posts of a fence, represented conventionally at 32, is selected to receive the stock 10 which is located with the offset 11 bearing against the post at one side thereof and the pin 19 thrust through one of the apertures 18 to bring the pin as closely as possible against the post at the opposite side. The stock 10 95 being formed of a flat bar and the weight of the extension which carries the stud 12 being located a considerable distance from the post, forces the stud end of the bar downwardly by gravity and thus firmly grips the post and anchors the device thereto and prevents the bar from slipping downwardly thereon. By providing a plurality of the apertures 18 it will be obvious that the pin 19 can be adjusted to enable the device to be 100 adapted to posts of varying sizes. By this means the stock 10 may be gripped upon the post with sufficient strength to prevent it from moving downwardly upon the post, and to hold the body until the strain is applied.

105 The wire 31 is then secured in the clip 27, as before described. The lever 110

- arm 15 is then moved into its forward position and the hook terminal 22 of the rod 20 engaged with one of the links of the chain 26, the latter being stretched as tightly as possible by hand. The lever arm 15 is then moved upon its pivot 12 toward the post 32 and thus applies strain upon the chain and the wire 31 supported thereby. When the strain is completed the other hook 10 23 is coupled to the chain and the movement of the lever reversed, which movement will apply strain to the rod 21 while the rod 20 is released. By thus alternately moving the lever 15 upon its pivot and coupling the 15 rods 20-21 alternately with the chain it will be obvious that a strong strain will be applied to the wire 31, and this strain can be repeated for any required distance within the range of the length of the chain 26. The 20 wire 31 will be stretched over a line of posts in the ordinary manner, and when the strain is completed the wire will be connected to the posts by staples in the usual manner.
- 25 By forming the offset 11 at an acute angle relative to the longitudinal axis of the stock 10 when the strain is applied the stock is drawn firmly against the supporting post, and the tendency to lateral displacement is obviated. This is an important feature of applicant's device and materially increases its efficiency and utility. Another advantage gained by the arrangement of the parts as shown is that the central line or the "pull"

point of the lever 15 is in substantial alignment with the center of the post 32, so that the "pull" is directly in alignment with the center of the post, consequently there is no lateral strain upon the post. 35

The improved device is simple in construction, can be inexpensively manufactured and applied and adapted to posts of varying sizes, as before stated. 40

Having thus described the invention, what is claimed as new is: 45

In a device of the class described, terminal transverse members and an intermediate transverse member, one of said terminal transverse members having a bearing and connected at one end by a longitudinal member to said intermediate transverse member and the other transverse member adapted to engage a stationary support at one side and connected at one end by a longitudinal member to the other end of the intermediate transverse member, a straining lever pivoted upon said bearing, and a holding member adjustably connected to the last mentioned longitudinal member and adapted to bear against the opposite side of the stationary support. 50 55

In testimony whereof I affix my signature in presence of two witnesses.
